APPARATUS FOR VAPORIZING LIQUID FUEL

Alwin B. Newton, Dayton, Ohio, assignor to
 Chrysler Corporation, Highland Park, Mich.,
 a corporation of Delaware

Application September 29, 1948, Serial No. 51,729

2 Claims. (Cl. 158—53)

1

This invention relates to liquid fuel burner systems in which a liquid fuel is converted to a gaseous state for burning in a conventional gas burner and more particularly to improved means for converting the liquid fuel to a gaseous state.

My copending application, Serial No. 655,722, filed March 20, 1946, now abandoned, discloses a device for converting liquid fuel to a gas before burning thereof. The present invention constitutes an improvement thereover. It is a well known phenomenon that when certain temperatures are attained in metals their magnetic properties diminish and the temperature at which this occurs is commonly referred to as the Curie point. It is an object of this invention to utilize this phenomenon to maintain the temperature of the device which vaporizes the oil within the desirable temperature range between temperatures which will produce full vaporizing of the oil and temperatures which will produce carbon. A vaporizing plate is maintained at the desired temperature and oil is brought in contact therewith for vaporization.

It is a further object of the invention to avoid local overheating of portions of the vaporizing plate as sometimes occurs with a thermostatically controlled plate of the type described in my copending application Serial No. 655,722.

It is an additional object of the invention to reduce the electric current consumption of devices of this type. In the device to be described herein only that portion of the plate which is cooled by the contact of liquid oil will be heated. The heating in this device is, of course, accomplished by induction rather than by resistance heating which would heat the entire plate.

The foregoing and other objects and advantages of the present invention may be ascertained from an inspection of the following specification taken in connection with the accompanying drawings wherein like numerals refer to like parts throughout.

In the drawings,

Fig. 1 discloses a schematic representation of the invention; and

Fig. 2 illustrates a control circuit.

A heating appliance 10 such as a furnace, boiler, water heater or the like, includes a heat exchanger 11 connected to a flue 13 and having a combustion space 12. Mounted within the combustion space 12 there is provided a gas burner 14 comprising a distributor space 15 and orifices 16. Gas under pressure is injected into the burner through a Venturi tube 17 and entrains therewith primary air of combustion. It is to be appreciat-

ed that the present invention may be applied to any operative form of burner having gas introduced thereto under pressure. The gas is introduced into the inlet of the venturi device 17 through a nozzle 18 communicating with the interior of a housing 19 defining a pressure vaporizing chamber having a fairly massive floor 20 adapted to be heated as will presently appear. Liquid fuel is introduced to the interior of the housing 19 and drips upon the floor 20 through a tube 25, preferably provided with a liquid trap double-U bend, extending from a liquid fuel metering device 26. A transformer 29 and stack temperature sensing device 30 are schematically illustrated in the relative positions that they would normally occupy. The floor 20 is made of a magnetic material so that its Curie point is above the temperature at which the liquid fuel will vaporize and below the temperature at which carbon will be produced. Means will be described herein for heating floor 20 by induction.

Referring to Fig. 2 there is disclosed a power line having a first primary transformer winding 35 and a second primary transformer winding 36 connected in parallel. The winding 35 provides reduced voltage to a control circuit through secondary windings 37. One end of the windings 37 is connected to a thermostat contact 38 adapted to contact a temperature sensing device 39, such as a bimetallic bar, when heat is desired in the room or other space to which heat is to be supplied under automatic control. Bar 39 is connected to a wire 40. A contact 43 is provided and makes contact with a contact carried on a rotatable arm 44 attached to the stack temperature sensing device 30 which comprises a thermostatic element such as a bimetallic spiral 45 adapted to rotate a rod 46 clockwise upon rise of temperature within the flue 13.

40 A wire 40 is connected to a contact 60 extending through the wall of a glass bulb 61 mounted upon a second arm 62 attached to the rod 46 for rotation in a clockwise manner upon rise of temperature in the flue 13. In the position illustrated the bulb 61 is tipped toward the left and a small quantity of mercury 63 contained therein thus bridges the gap between contact 60 and a second contact 64 extending through the wall of the tube. Contact 64 is connected by means of a wire 65 to a temperature sensing element 66 preferably located adjacent floor 20 and adapted to contact a fixed contact 67. The contact 67 is connected to a wire 68 leading to a heater element 69 positioned within the fuel metering device 26, the opposite end of the resistance heater

69 being connected by wire 70 to wire 54 leading back to the secondary winding 37. Thus, when heat is required and thermostat 39 makes contact the heater 69 will be energized if thermostatic element 66 makes contact and bulb 61 has not rotated far enough clockwise to cause the mercury 63 to run to the right end of the bulb 61.

Contact 67 is also connected by a wire 42 to the contact 43. When there is no combustion occurring contact 43 and arm 44 are engaged as illustrated, but upon a rise in temperature within the flue sufficient to indicate that combustion has taken place arm 44 will be rotated away from contact 43. The arm 44 connects contact 43 to wire 50 leading to the solenoid of a switch 51 adapted to close the parallel circuit leading to primary winding 36. As soon as thermostat 39 calls for heat the secondary winding 52 will be energized to cause a spark at the spark device 53 located adjacent the orifices 16 of the gas burner so that an ignition spark would be provided in readiness for gas issuing from the burner. From the solenoid of the switch device 51 a wire 54 leads back to the transformer winding 37.

The secondary windings 37 are connected to a wire 75 leading through a condenser 76 to an induction coil 77 positioned adjacent the floor 20. When current of the proper frequency is admitted to coil 77 floor 20 is heated by induction. Coil 77 has its opposite end connected by wire 79 to the wire 54 leading back to transformer 37. The coil 77 upon being energized raises the temperature of any portion of floor 20 having a temperature below the Curie point of the metal therein. When the Curie point is reached the heating automatically discontinues as an incident to the diminishing magnetic properties of the heated metal. The hot floor 20 vaporizes fuel dripping thereon. The vaporized fuel is maintained under pressure by the head in tube 25 and escapes through the nozzle 18 into the gas burner where it is consumed in accordance with known principles of gas combustion. The liquid fuel is prevented from flowing into the chamber 19 until slightly after a predetermined minimum temperature is reached. When the predetermined minimum temperature is reached element 66 closes with contact 67 and resistance 69 thereupon becomes energized. The resistance 69 heats a bimetallic bar 80 connected by a rod 81 to a valve device 82 adapted to permit metered flow of liquid fuel into the tube 25. The reaction of element 80 is preferably very rapid so that metered quantities of fuel will flow shortly after element 66 closes the circuit to element 69.

Contact 67 is also connected to wire 85 leading to a heater 86 adjacent the thermostatic element 39, the other end of which is connected by means of wire 87 to wire 54 leading back to a secondary winding 37, so that heater 86 is energized simultaneously with heater 69. The effect of heater 86 is so calculated as to raise the closing temperature of the element 39 several degrees above the temperature for which it is set so as to prevent operation of the burner for mild fluctuations in temperature since the thermostat will open immediately after closing and remain open unless there is a continued demand for heat, and likewise will open when the room temperature is a few degrees lower than the thermostat setting so as to prevent oversupply of heat. The heater 86 thus provides means for modulating or evening the heat supplied to a dwelling or the like, and op-

erates in accordance with well-known principles.

The vaporizing chamber having been raised by energization of heater 77 to a degree sufficient to instantaneously vaporize the fuel when the metered flow of fuel occurs the fuel flashes into gas and is ignited at the orifices 16. Thus when thermostatic control 39 firmly calls for heat there will first of all be supplied an igniting spark at spark gap 53. Combustion will cause the temperature within the flue 13 to raise sufficiently to open the circuit at contact 43 thus cutting off the ignition spark. If the temperature in the flue passes a predetermined high limit the bulb 61 will rotate beyond the vertical and open the circuit to the resistance 69 thereby causing cessation of fuel flow. Coil 77 will remain energized thus causing the vaporizing chamber to rise in temperature to a predetermined high limit at which time the magnetic properties of the floor 20 will diminish and further inductive heating will not be possible. If, on the other hand, the room temperature or the temperature of the boiler or other device indicates that heat is no longer required element 39 will open the entire control circuit regardless of the position of the bulb 61 or the temperature of the vaporizing chamber 19 and the metering device will cease operating.

The switch 55 is operated by a rod 90 mounted upon a bucket 91 carried by a lever 92 pivoted at 93 and counter-balanced by a spring 94, the device being located in the closed chamber 28 in such position as to cause the bucket 91 to receive overflow from the chamber 19 through the overflow tube 27. Thus if the chamber 19 overflows, indicating failure of the system to operate satisfactorily, the switch 55 will open all of the control circuits and no further operation can occur until a serviceman corrects the difficulty.

Switch 55 is also in series with the switch 56 which provides an ignition failure safety device. Switch 56 is normally closed and is adapted to be opened by a time delay relay 100 connected across the transformer winding 37 through wires 101 and 102 so that it will be energized immediately upon closure of thermostatic element 39 and will open switch 56 to render the system inoperative a predetermined interval of time after current is supplied to the control circuit and heaters, provided combustion fails to take place. If combustion takes place a thermo-electric generating device 103, which is so positioned as to generate a current when there is a flame at the burner 14, will de-energize relay 100 through means of a switch 104 operated by a solenoid 105. Other forms of delayed action devices such as clock-motors and the like may be substituted for the relay 100, and other forms of switch actuating devices such as electronic tubes adapted to be energized upon combustion may be substituted for the thermocouple device 103, without departing from my invention.

A feature (not shown) of modern stack switches is that arms 44 and 62 may be connected to rod 46 through the medium of slip-clutch devices, and are limited in movement by suitable stops. Thus arm 44 may move through an arc representing a rise of 50 degrees and then will be held against further rotation, so that upon a temperature drop of 50 degrees, ignition will be reestablished. Also arm 62 will be constrained to move in an arc sufficient to cause breaking of the circuit at the desired temperature regardless of the extent of further rotation of rod 46, and

may reestablish the circuit after a temperature drop of, for example, 50 degrees.

Having illustrated and described a preferred form of my invention I claim all such modifications thereof as come within the scope of the appended claims.

I claim:

1. Apparatus for vaporizing liquid fuel preparatory to combustion in a burner of the type adapted to burn a gaseous fuel introduced thereinto under pressure comprising a closed container in which vapor pressure may build up, said container having a floor therein formed of magnetic material and having a nozzle forming an outlet through which the resulting vapor is discharged solely by the vapor pressure built up in said container, a liquid fuel metering device operable to deliver liquid fuel to said container and into contact with said floor, a source of electric energy and an electric coil connected to said source and located in proximity to said floor and operable when energized to subject said floor to a magnetic field and to inductively heat said floor until it has attained a temperature corresponding to its Curie point.

2. A vaporizing device adapted to deliver gas under pressure to the inlet of the gas burner of a heating appliance comprising a closed container having a floor formed of magnetic material which loses its magnetic properties at a prede-

5

terminated temperature and a nozzle communicating with the interior of said container and adapted to deliver gas to said gas burner inlet, the gas being discharged from said container through said nozzle solely by vapor pressure built up in said container, a liquid fuel metering device, tubing connecting said liquid fuel metering device to said container above said floor to accommodate the dripping of fuel on to said floor and electrical means for heating said floor by induction.
